ELECTRIC FLUTING MACHINE

Ralph Otto Clark and Lucie Anna Clark,
Estherville, Iowa

Application April 4, 1936, Serial No. 72,814

1 Claim. (Cl. 219—25)

This invention relates to electric fluting machines and has for an object to provide a machine of this type which may be clamped to an ironing board and which may be hand operated to form neat accurate flutes or pleats in window curtains and other articles.

A further object is to provide a fluting machine in which the fabric to be fluted is operated upon by two top rollers which are located at opposite sides of the vertical center of a lower roller and which are provided with cogs engaging cogs of the lower roller, the upper rollers being electrically heated and being yieldably pressed downward at the ends so that they may be tilted vertically on their axes to respond to inequalities such as hems, seams and the like, in the article to be fluted.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawings forming part of this specification,

Figure 1 is a front elevation of the improved fluting machine in applied position on an ironing board.

Figure 2 is an end elevation of the machine with the rollers shown in dotted lines.

Figure 3 is a longitudinal sectional view taken on the line 3—3 of Figure 2.

Figure 4 is a cross sectional view taken on the line 4—4 of Figure 3 showing the heating coils of the rollers.

Figure 5 is a cross sectional view taken on the line 5—5 of Figure 3 showing the yielding means for holding the upper rollers pressed downwardly and showing the conductor rings and brushes for electrically connecting the heating coils together.

Referring now to the drawings in which like characters of reference designate similar parts in the various views, 10 designates a bracket having a foot 11 at the bottom through which a set screw 12 is passed. A pair of lugs 13 are formed integral with the bracket and are adapted to be placed upon the upper side of an ironing board 14, as best shown in Figure 1. The set screw 12 is then screwed up tight against the ironing board to anchor the bracket to the ironing board. The lugs 13 are connected at the front end by a plate 15, as best shown in Figures 2 and 3. A lower roller 16 is fixed to a shaft 17 which is journaled at the ends in respective openings in the plate 15

and in the bracket 10. The lugs 13 have concave inner faces 18 which house the lower side of the roller. As best shown in Figure 2 the roller is provided with longitudinal cogs 19.

A cover plate 20 is fixed at one end to the top of the bracket by means of a screw 21 and is provided at its opposite end with a depending flange 22.

A pair of shafts 23 are journaled in vertical slots 24 formed in the flange 22 and are provided with bearing bushings 25 of insulating material which are mounted in slots 26 in the bracket 10, as shown best in Figure 4. Hollow rollers 27 are fixed to these shafts, as best shown in Figure 2, and these rollers are located above and at opposite sides of the vertical center of the lower roller 16. The hollow rollers are provided with heating coils 28, the ends of which are brought through their respective bushings 26 and are connected to respective conductor rings 29 and 8, fixed to the bushings 25. The upper rollers are provided with cogs 30 which mesh with the cogs 19 of the lower roller 16.

As best shown in Figure 5, a leaf spring brush 31 is mounted on a block of insulation 32 which is fixed to the bracket 10 by screws 33, the ends of the brush bearing upon the inner conductor rings 8. Brushes 34 bear upon the outer conductor rings 29. Current is conducted to the brushes 34 through a cable 35 which may be plugged in to any convenient outlet.

By referring to Figure 3 it will be seen that a pair of spring bars 36 are secured respectively to the flange 22 and to the wall of a casing 37 which houses the conductor rings and brushes, and these spring bars exert downward pressure upon the ends of the shafts of the upper rollers 27 to permit the upper rollers to yield vertically and also to tilt somewhat to conform to inequalities such as seams, hems, or the like, in the material being fluted.

A crank handle 38 is fixed to the shaft 17 of the lower roller and may be manually operated to rotate the rollers to feed the material between them.

In operation the material to be fluted, such as lace curtains or the like, may be passed in between the heated upper rollers and the bottom roller and the crank handle 38 may then be rotated to feed the material through the rollers. The meshing cogs of the rollers deform the material and shape it to provide flutes or pleats of uniform length and width during progress of the material between the rollers.

From the above description it is thought that

the construction and operation of the invention will be fully understood without further explanation.

What is claimed is:

- 5 An electric fluting machine comprising a bracket, means for securing the bracket to a support, a cover plate fixed at one end to the top of the bracket and provided at its free end with a depending flange, a lower roller having cogs and 10 being rotatably mounted in the bracket, a pair of hollow top rollers rotatably mounted on the bracket and on the flange and having cogs, electrical heating coils confined within the top rollers and each having their ends brought out from the rollers at the same end of the rollers, spaced

conductor rings for each coil fixed upon and insulated from the associated shaft, brushes engaging the conductor rings for supplying current to the coils, a housing for the conductor rings, there being slots in the bracket and in the flange 5 permitting the top rollers to yield vertically and cant on their axes, springs carried by the housing and by the flange and bearing upon the rollers to yieldably hold the rollers at their lowest limit of movement, and means for rotating the lower 10 roller to feed the material to be fluted between the lower roller and the top rollers.
